UNITED STATES PATENT OFFICE

171,175

FISHING OUTRIGGER

Paul D. Wells, Oakland, Calif.

Application November 15, 1952, Serial No. 22,300

Term of patent 14 years

(Cl. D71—1)

To all whom it may concern:

Be it known that I, Paul D. Wells, a citizen of the United States, residing at Oakland, in the county of Alameda, and State of California, have invented a new, original, and ornamental Design for a Fishing Outrigger, of which the following is a specification, reference being had to the accompanying drawing, forming a part hereof.

Fig. 1 is a side elevation view of a fishing outrigger showing my new design.

Fig. 2 is a top view of the fishing outrigger.

I claim:

The ornamental design for a fishing outrigger, substantially as shown.

PAUL D. WELLS.
